UNITED STATES PATENT OFFICE.

EDWARD E. PINKERTON, OF CHICAGO, ILLINOIS, ASSIGNOR OF ONE-HALF TO CHARLES HARKER HUDSON, OF CHICAGO, ILLINOIS.

FOLDING BOX.

1,337,368.

Specification of Letters Patent. Patented Apr. 20, 1920.

Application filed August 11, 1915. Serial No. 44,921.

To all whom it may concern:

Be it known that I, EDWARD E. PINKERTON, a citizen of the United States, and a resident of the city of Chicago, county of Cook, and State of Illinois, have invented certain new and useful Improvements in Folding Boxes, of which the following is a specification.

My invention relates to improvements in folding boxes, and has for its object the provision of an improved folding box especially adapted for receiving elongated articles such as music rolls and the like.

The invention consists in the combinations and arrangements of parts hereinafter described and claimed.

The invention will be best understood by reference to the accompanying drawings forming a part of this specification, and in which,

Figure 1 is a perspective view of a box embodying my invention,

Fig. 2, an enlarged vertical section taken through one end of said box,

Fig. 3, an enlarged section taken on the plane 3—3—3 of Fig. 1,

Fig. 4, an enlarged section taken on the plane 4—4—4—4 of Fig. 1, and

Fig. 5, a plan view of the blank from which the box is formed.

The preferred form of construction, as illustrated in the drawings, comprises a blank of cardboard or similar material formed into a bottom member 5 having a side member 6 along one edge thereof. A top member 7 is formed along the edge of side member 6 and a side member 8 is formed along the edge of top member 7. End flaps 9, 10 and 11 are formed at corresponding ends of the members 6, 7 and 8 and are adapted to be folded across the corresponding end of the box as indicated, the flaps 9 and 11 being preferably folded before flap 10 so that flap 10 overlies the others. The bottom member 5 is provided at the corresponding end with a flap 12 having a tongue 13 for securing the flap in place. The top member 7 is cut away at the side opposite flap 10 to form a space 14 for a purpose to be presently explained. A second side member 15 is formed at the other side of bottom member 5 and top members 16 and 17 arranged in order, as shown. The top member 16 is provided with a transverse crease 18 forming the outer portion thereof

into a cover member 19 hinged thereto along the line 18, said hinge joint being preferably reinforced by a cloth strip 18'. Substantially triangular flaps 20 are formed at the sides of cover member 19 from the corresponding portions of side members 15 and 17 and end flaps 21 and 22 are formed at the free ends of flaps 20. An end flap 23 is formed at the free edge of cover flap 19 and is provided at its free edge with a locking tongue 24 creased along the line 25. An opening 21' and a slit 26 are formed respectively in flaps 21 and 22 for co-operation with the tongue 24 in locking the flaps 21, 22 and 23 in place to constitute the end of a drop cover for the box, as indicated in Figs. 1 and 2. A flap 27 is formed at the corresponding end of bottom member 5 and is arranged to fit within the drop cover thus formed.

In making up the box the members 6, 7 and 8 are first folded at right angles to each other into tubular form to co-operate with bottom member 5 to constitute the sides and top of the box. Then members 15, 16 and 17 are similarly folded over the members 6, 7 and 8, the side members 15 and 17 being secured by glue or otherwise to the side members 6 and 8. This forms the box ready for shipment in which condition it may be folded flat with the flaps constituting the ends of the box laid out straight, as will be readily understood.

When it is desired to form the completed box, the end flaps 9 and 11 are folded inwardly with the flap 10 thereover and flap 12 folded over flap 10 and the tongue 13 inserted between the top members 7 and 16, as indicated in Fig. 4. To complete the other end of the box, the flaps 21 and 22 are folded inwardly and the flap 23 folded thereover, the tongue 24 being inserted through the opening 21' and the slit 26, the crease 25 facilitating such insertion without breaking of said tongue. This forms a drop cover for the end of the box hinged along the line 18, as shown in Fig. 1. When it is desired to close the box after an article has been placed therein, the flap 23 is first folded up over the corresponding end and the drop cover member swung over this flap. The box thus produced can be manufactured economically and will be found to be strong and durable in use. By gluing the entire side members 15 and 17 to the corresponding side mem-

bers 8 and 6 throughout their entire area, very stiff sides will be formed on the box.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A folding box formed from a single blank of material comprising a bottom member; a side member at one edge of said bottom member; a top member at the edge 20 of said side member; a side member at the edge of said top member; means at one end of said members for closing the corresponding end of the box; and a drop cover member for the other end of the box formed 25 from the corresponding portions of said top member and the adjoining portions of said side members, substantially as described.

2. A folding box comprising a bottom member; a side member at one edge of said bottom member; a top member at the edge of said side member; a side member at the edge of said top member; a second side member at the other edge of said bottom member; a second top member at the edge 35 of said second side member; a second side member at the edge of said second top member, overlying side members being secured together; means at one end of said members for closing the corresponding end 40 of the box; and a drop cover member for the other end of the box formed from the corresponding portions of said second top member and the adjoining portions of said second side members, substantially as de- 45 scribed.

3. A folding box comprising a bottom member; a side member at one edge of said bottom member; a top member at the edge of said side member; a side member at the edge 50 of said top member; a second side member at the other edge of said bottom member; a second top member at the edge of said second side member; a second side member at the edge of said second top member; means at one end of said members for closing the corresponding end of the box; flaps at one end of said first side members and said first top member folding across the corresponding end of the box; a similar flap on said bottom member provided with a tongue, 55 there being a corresponding opening and slit in the associated flaps to receive said tongue and form the corresponding end of the box; and a flap on the corresponding end of said bottom member folded within said drop cover member, substantially as de- 60 scribed.

6. A folding box comprising a bottom member; a side member at one edge of said bottom member; a top member at the edge 65 of said side member, said top member being cut away at one end to form an open space; a side member at the edge of said top member; a second side member at the other edge of said bottom member; a second top member at the edge of said second side member; a second side member at the edge of said second top member; means at one end of said members for closing the corresponding end of the box; flaps at one end of said first side members and said first top member folding across the corresponding end of the box; a similar flap on said bottom member provided with a tongue, 70 there being a corresponding opening and slit in the associated flaps to receive said tongue and form the corresponding end of the box; and a flap on the corresponding end of said bottom member folded within said drop cover member, substantially as de- 75 scribed.

said second side members, substantially as described.

4. A folding box comprising a bottom member; a side member at one edge of said bottom member; a top member at the edge 70 of said side member; a side member at the edge of said top member; a second side member at the other edge of said bottom member; a second top member at the edge of said second side member; a second side member at the edge of said second top member, overlying side members being secured together; means at one end of said members for closing the corresponding end of the box; flaps at one end of said first side 80 members and said first top member folding across the corresponding end of the box; a similar flap on said bottom member provided with a tongue inserted between said top members; and a drop cover member for the other end of the box formed from the corresponding portions of said second top member and the adjoining portions of said second side members, substantially as described.

5. A folding box comprising a bottom member; a side member at one edge of said bottom member; a top member at the edge of said side member, said top member being cut away at one end to form an open 90 space; a side member at the edge of said top member; a second side member at the other edge of said bottom member; a second top member at the edge of said second side member; a second side member at the edge of said second top member; flaps at one end of said first side members and said first top member folding across the corresponding end of the box; a similar flap on said bottom member provided with a tongue, 95 inserted between said top members; and a drop cover member for the other end of the box formed from the corresponding portion of said second top member and the adjoining portions of said second side members; flaps at the ends of said portions of said second side members folded across the corresponding end of the box; a flap on the corresponding end of the top of said drop cover member provided at its free edge with a tongue, 100 there being a corresponding opening and slit in the associated flaps to receive said tongue and form the corresponding end of the box; and a flap on the corresponding end of said bottom member folded within said drop cover member, substantially as de- 105 scribed.

6. A folding box comprising a bottom member; a side member at one edge of said bottom member; a top member at the edge 115 of said side member, said top member being cut away at one end to form an open space; a side member at the edge of said top member; a second side member at the other edge of said bottom member; a second top member at the edge of said second side member; a second side member at the edge of said second top member; means at one end of said members for closing the corresponding end of the box; flaps at one end of said first side members and said first top member folding across the corresponding end of the box; a similar flap on said bottom member provided with a tongue, 120 there being a corresponding opening and slit in the associated flaps to receive said tongue and form the corresponding end of the box; and a flap on the corresponding end of said bottom member folded within said drop cover member, substantially as de- 125 scribed.

ond top member at the edge of said second side member; a second side member at the edge of said second top member, overlying side members being glued together; flaps at 5 one end of said first side members and said first top member folding across the corresponding end of the box; a similar flap on said bottom member provided with a tongue inserted between said top members; a drop 10 cover member for the other end of the box formed from the corresponding portion of said second top member and the adjoining portions of said second side members; flaps at the ends of said portions of said second 15 side members folded across the corresponding end of the box; a flap on the correspond-

ing end of the top of said drop cover member provided at its free edge with a tongue, there being a corresponding opening and slit in the associated flaps to receive said 20 tongue and form the corresponding end of the box; and a flap on the corresponding end of said bottom member folded within said drop cover member, substantially as described.

25

In testimony whereof I have signed my name to this specification in the presence of two subscribing witnesses.
